UNITED STATES PATENT OFFICE

2,123,278

STITCHDOWN SHOE

James P. Fredericksen, Quincy, Mass., assignor to
United Shoe Machinery Corporation, Paterson,
N. J., a corporation of New Jersey

Application October 26, 1936, Serial No. 107,639

1 Claim. (Cl. 36—16)

The present invention relates to stitchdown shoes.

It is a common practice in the manufacture of stitchdown shoes having end stiffeners (that is box toes and counters) to provide such stiffeners with outturned bottom margins which extend to the edge face of the outsole or intermediate sole. This additional substance in the end portions of the outwardly extending margin of the shoe bottom causes the edge face of the shoe bottom to be considerably wider at the ends of the shoe than at the sides of the shoe and gives the ends of the shoe bottom a heavy or bulky appearance which is generally considered undesirable. It is an object of the present invention to obviate this objectionable condition by providing a stitchdown shoe in which the edge face of the outwardly extending margin of the shoe bottom is no wider at the ends of the shoe than at the sides of the shoe.

With the above object in view, the invention comprises a stitchdown shoe, herein illustrated as a three-soled shoe, comprising an extension sole and an insole which is substantially shorter than the extension sole and extends only from the tip line to the rearward extremity of the shank but is of the same width as the extension sole and extends outwardly to the edge face of the extension sole at opposite sides of the shoe. The outturned margins of the upper materials at the ends of the shoe are secured to said extension sole while the outturned margins of the upper materials at the sides of the shoe are secured to the margins of the insole. In the illustrated shoe the thickness of the insole is substantially the same as the thickness of the outturned margins of the end stiffeners and it will be understood that the illustrated construction provides a stitchdown shoe having a sole margin the thickness of which in the region of the end stiffeners is substantially the same as the thickness of the side portions of the sole margin.

The invention will now be described with reference to the accompanying drawing and will be pointed out in the appended claim.

In the drawing,

Fig. 1 is a perspective view of a last with an insole attached thereto, part of an upper, not yet lasted, and part of a lining drawn over the end portions of the last and secured to the insole;

Fig. 2 is a sectional view taken on the line II—II of Fig. 1;

Fig. 3 is a perspective view of an insole having no heel portion;

Fig. 4 is a perspective view of an insole lacking both heel and toe portions;

Fig. 5 is a perspective view of a three-soled stitchdown shoe, parts of which are broken away in order to illustrate the shoe construction; and

Fig. 6 is a side elevation, partly in section, illustrating the toe portion of a three-soled stitchdown shoe such as that illustrated in Fig. 5.

Referring to Fig. 5, the illustrated shoe comprises an upper 10 which may be of any construction commonly employed in stitchdown shoe manufacture but as herein illustrated is an upper of the blucher type. The entire bottom margin of the upper is flanged outwardly as indicated at 12. The upper 10 is provided with a toe stiffener 14 and a heel stiffener or counter the outturned margin of which is indicated at 16. The upper 10 is also provided with a lining 18 the end portions of which may be turned outwardly, as indicated at 20 in Fig. 5, or inwardly as indicated at 22 in Fig. 1. If the end portions of the lining 18 are turned inwardly they are secured by cement to the end portions of an insole such, for example, as the insole 24 illustrated in Fig. 1. If the end portions of the lining 18 are turned outwardly, as indicated in Fig. 5, they are secured to the margin of an extension sole such, for example, as the intermediate sole 26 illustrated in Fig. 5.

In order that the edge face of the shoe bottom may be of a uniform width, as illustrated in Fig. 6, the side portions of the insole 24 are provided with outwardly extending margins 28 (Fig. 1) which in the finished shoe extend to the edge face of the shoe bottom, as illustrated in Fig. 6. The margins 28 extend substantially from the tip line at the toe portion of the shoe to the rearward extremity of the shank portion of the shoe and terminate in end faces 30 which are arranged at right angles to the adjacent side edge faces of the margins 28 and are beveled, as illustrated in Figs. 5 and 6, in order that the division between the margins 28 of the insole and the outturned margins of the end stiffeners shall not be objectionably abrupt. If the end portions of the lining are to be flanged outwardly, as illustrated in Fig. 5, the insole, if desired, may extend only from the tip line to the rearward extremity of the shank portion of the shoe, as illustrated in Fig. 4, or it may extend from the rearward extremity of the shank forwardly to the toe end of the shoe, as illustrated in Fig. 3.

It will be understood that the illustrated shoe lends itself readily to various methods of manufacture. In accordance with one method which may be employed, an insole, for example the in-

sole 24 illustrated in Fig. 1, is temporarily attached to the bottom of a last by means of tacks 32. An upper such, for example, as the upper 10 illustrated in Fig. 5, is then assembled on the last. The toe portion of the upper may have been pre-formed before the upper is assembled on the last or it may be shaped by tensioning it over the last in any known manner after it is assembled thereon. If the end portions of the lining 18 are to be lasted inwardly over the insole, as illustrated in Fig. 1, slits are now formed in the margin of the lining adjacent to the ends 30 of the outwardly extending side margins 28 of the insole. The lasting of the end portions of the lining may be performed by supporting the last on a bench spindle, drawing the lining over the insole by means of hand pincers, and adhesively securing the overlasted margins of the lining to the margins of the end portions of the insole. If the end portions of the lining are to be flanged outwardly, as illustrated in Fig. 5, it is, of course, unnecessary to slit the margin of the lining adjacent to the ends of the side margins of the insole, the beveled end faces 30 of the margins 28 of the insole enabling the lasting operator readily to position the outturned margin of the lining between the overlying and underlying materials in the margin of the shoe bottom, as illustrated in Fig. 6. When the lining 18 is flanged outwardly it is lasted with the other upper materials, the entire shoe preferably being lasted in one operation, for example in a machine such as that illustrated and described in United States Letters Patent No. 1,864,510, granted June 21, 1932, upon an application of Bernard T. Leveque. This machine forms a chainstitch

seam 34 (Fig. 5) which secures the upper 10, the toe stiffener 14 and the lining 18 to the toe portion of the intermediate sole 26 and secures the upper and lining together with the margins 28 of the insole to the side portions of the intermediate sole and also secures the heel stiffener together with the upper and lining to the heel portion of the extension sole. Preferably the shoe is completed by attaching an outsole 36 and a mock welt 38 to the margin of the shoe bottom, for example by means of a lockstitch seam 40.

While the invention is herein illustrated in its application to the manufacture of three-soled stitchdown shoes, it is to be understood that the invention is not thus limited in its scope but is applicable, as well, to the manufacture of two-sole stitchdown shoes. For example, the outturned margins of the upper materials could be attached by cement to the margins of the sole 26 and permanently secured thereto by a lockstitch seam, in which case the sole 26 could, if desired, be the outsole of the shoe.

Having thus described my invention, what I claim as new and desire to secure by Letters Patent of the United States is:

A stitchdown shoe having an extension sole and an insole which extends only from the tip line to the rearward extremity of the shank and which extends outwardly to the edge face of the extension sole, the outturned margins of the upper materials at the ends of the shoe being secured to the extension sole while the outturned margins of the upper materials at the sides of the shoe are secured to the margins of the insole. 35

JAMES P. FREDERICKSEN.
